UNITED STATES PATENT OFFICE.

JAMES E. ECKERSLEY, OF ABERDEEN, WASHINGTON, ASSIGNOR OF ONE-HALF TO
ALEXANDER POLSON, OF HOQUIAM, WASHINGTON.

WOOD-CUTTING KNIFE.

Application filed August 19, 1927. Serial No. 214,184.

In knives heretofore used for veneers and in cutting of wood for shingles, slats, etc., there is one fault that I have noticed and that is this: They have not sufficient draw 5 to cut the fibre of the wood as they pass through, because after the knife has passed through the block of wood there will be seen a number of fibres hanging over the edge of the knife, and this means that this 10 portion of the knife, no matter how sharp it may be, has not cut its way through the wood, but on the contrary has pushed that portion of the knife fibre and all through the wood without cutting and by so doing has 15 broken the grain.

I have found that in the block of wood, by using a knife with a clearance according to my invention, there is not more than one half thousandth of an inch variation in 20 cutting stock .075", whereas in cutting the same block with the knives heretofore used that there was from one and one half to two and one half thousandths difference.

This clearance in my improved knife gives 25 the knife free cutting, whereas the knives heretofore used seem to have a binding effect which prevents them from running freely which results in an unevenness in thickness of the stock.

30 In the drawings:

Figure 1 is a bottom plan view of a knife embodying my invention.

Figure 2 is a vertical central sectional view through Figure 1.

35 Figure 3 is an enlarged sectional view of the upper end of Figure 2.

Figure 4 is an enlarged detail sectional view of the cutting edge of the knife.

Figure 5 is a bottom plan view of a straight 40 knife embodying my invention.

Figure 6 is an end view of Figure 5.

Figure 7 is an enlarged detail sectional view of the cutting edge portion.

The invention in all of the figures is the 45 same, therefore I will not describe each detail specifically in Figures 5, 6 and 7, but in these figures I will use the same reference numeral, only in Figures 5, 6 and 7 I will add a prime to the numeral used to designate a 50 corresponding part or construction.

The reference numeral 10 designates a circular or disc like knife embodying my invention, having the cutting edge 11, which edge 55 when in action has a shearing effect, which causes the fibre of the material to be cut by

shearing instead of being pushed through the material by hanging over the edge of the knife which causes the other fibre or grain on the material to be broken, as herein pointed out.

80 The knife is provided with suitable bolt or screw openings 13 through which screws may be passed to fasten the knife to a collar mounted on a shaft, the collar and shaft not being shown in the drawings. It will be 85 noted that the screw is to be counter sunk in the knife the purpose of which is to prevent the top of the screw scratching the material while the knife is operating.

As more clearly seen in Figure 4, the cutting edge is designated by the reference numeral 11, while the heel is designated by the reference number 12. It will be noted that the cutting edge has one straight side 14, 70 which is the side of the knife next to the block 75 of material operated upon, which side 14 extends a certain distance back to a point 15 where there is a decidedly sharp drop, the purpose of which is for clearance to relieve friction which produces heat that sets up a 80 tension in the knife.

The cutting edge portion is hollow ground as at 16 on the bottom side of the knife, the purpose of which is to give the stock relief 85 in cutting. Attention is called to the fact that this hollow ground portion does not extend to the extreme cutting edge 11, but extends only from the point 17 to the heel 12. The surface between the cutting edge 11 and the point 17 is ground at an angle to conform with the general grind of bevel and insures maximum strength in the very cutting edge which, otherwise would be too thin for general or commercial use.

90 In Figures 5, 6 and 7 I have shown my invention embodied in a straight knife A, and for corresponding parts in these figures the reference numbers used in the other figures have been primed.

95 This invention after commercial tests has been found to overcome the known defects and objections of knives heretofore used, and has given universal satisfaction and found to produce a better result.

I am aware that certain changes may be 105 made in my improved knife without departing from the scope of the appended claims.

What I claim is:

110 1. In a knife, a cutting edge portion having a flat top face, a bottom concave face ter-

minating short of the cutting edge portion, and a cutting edge substantially triangular in cross section and flat throughout its surface area.

5. 2. In a knife, a cutting edge portion having a flat top face extending to the cutting edge and terminating away from the cutting edge in an abrupt drop to the plane of the

knife body, a bottom face having a concaved face terminating short of the cutting edge in one direction, and extending in the other direction to a point on the knife body back of the abrupt drop of the top face. 10

In testimony whereof I affix my signature.

JAMES E. ECKERSLEY.
